UNITED STATES PATENT OFFICE.

WILLIS STUTSON, OF WINNETKA, ILLINOIS.

COMBINATION DOOR RETAINER AND BUMPER.

Application filed November 27, 1925. Serial No. 71,616.

This invention relates to combination door retainers (known in the trade as "dovetails") and bumpers, particularly adapted for use between the door and its frame in an automobile or other vehicle to prevent shock attendant upon the closing of the door, and to prevent rattling or other relative movements of the door in its closed position.

The description so far as concerns subject matter relative to the retaining member, may be found in greater detail in my application Serial No. 62,497, filed October 15, 1925.

It is apparent that in combining these heretofore separate elements (dovetail and bumper) into one, the cost of manufacturing and the cost of installation are greatly lessened. It is also believed that the positioning of these elements in such relation, will effect more desirable results.

One of the objects of my invention is to provide a combination door retainer and bumper of a design which will be relatively simple in form and inexpensive to manufacture.

A further object of my invention is to provide a combination door retainer and bumper of a design which will be easily and inexpensively installed.

A further object of my invention is to provide a combination door retainer and bumper in which the members in combination are arranged in such a relation as to more effectively eliminate rattling, the retainer member eliminating any vertical movement of the door and the bumper member eliminating any horizontal movement of the door.

Other objects and advantages will be apparent from the accompanying drawings, in which:

Figure 1 is a vertical, sectional view through my device in a closed position when mounted in the door and frame member;

Fig. 2 is a horizontal sectional view taken on the line 2—2 of Fig. 1, showing the door in a partially open position; and

Fig. 3 is a perspective view of the resilient tongue and bumper members.

Referring to the drawings in detail, the construction shown therein comprises a yielding, resilient, projecting device 10 of spring steel material secured to the swinging edge of the door 11; a rubber bumper 12 mounted within the projecting device, and a resilient receiving device 13 secured in a recess in the door frame 14.

The resilient projecting device is formed

of a single piece of sheet material shaped to provide two leaf spring members 15, and a common base portion 16 uniting the leaf spring members, said base portion being suitably mounted into the body portion of the door by means of screws 16'. The holes in the base portion, through which the screws project, are formed by stamping a larger hole in the bottom thickness of the metal and a smaller hole in the upper thickness of the metal and pressing the overlapping portion of the smaller diameter into the larger hole. This provides a conical shaped seat for the head of the screw thereby eliminating the otherwise necessary operation of countersinking the hole.

Between the two leaf spring members 15, is held the securing portion or stem 17 of the rubber bumper 12, this securing portion being of a shape to conform to the contour of the leaf spring members and of sufficient size to make a snug fit. At one end of the securing portion of the bumper and formed integrally therewith is an elongated cushioning portion or head 18 adapted to seat itself between the casing of the receiving device 13 and a flange 19 of the door, upon the closing of the door. This cushioning portion is of a sufficient width to hold in a somewhat spaced relation the door and its frame, thereby relieving the shock attendant upon the closing of the door.

The receiving device comprises a stamped sheet metal casing 20, seated in a recess in the door frame 14 and having upper and lower compartments in which are seated a pair of fiber blocks 21, suitably held in position and spaced a sufficient distance apart to snugly receive the leaf spring portions and bumper of the projecting member when the door is closed. This action results in compressing the leaf spring members toward each other, which action also compresses the securing portion of the bumper member, thereby giving more body or resistance to the leaf spring members.

It is apparent that in closing the door the resiliency of the elongated cushioning portion of the rubber bumper will absorb the shock attendant on its closing and that while in the closed position, the resilient projecting device held between the two fiber blocks of the receiving member, will effectively prevent rattling due to vertical movement between the door and its frame member, while the bumper member will effectively prevent rat-

ting due to horizontal movements between the door and its frame member.

While I prefer embodying my invention in the device herein shown and described, I do not desire to be limited to this structure or to the details thereof, as various other equivalent structures will be apparent to one skilled in the art and consequently the invention is to be limited only by the scope of the appended claims.

I claim:

1. The combination with the hinged side door of an automobile, said door being provided with a flange at its edge, of a yielding dovetail construction comprising a receiving device, a projecting spring device which snugly engages said receiving device, said projecting device having a recess therein and a bumper member having a securing portion held in said recess and a cushioning portion backed up by the flange on said door.

2. The combination with the hinged side door of an automobile, said door being provided with a flange at its edge, of a yielding dovetail construction comprising a receiving device, a projecting spring device which snugly engages said receiving device and a bumper backed up by said flange and engaging the receiving device of said yielding dovetail construction when door is closed.

3. The combination with the hinged door of an automobile mounted to swing about a substantially vertical axis and its frame of a yielding dovetail construction comprising a receiving device and a projecting device which engages the receiving device when the door is closed; said projecting device comprising a pair of spring tongues yieldable vertically about axes transverse to the plane of the door to move toward and from each other, and a cushioning body of yieldable material interposed between said spring tongues thereby giving more resistance to the spring members.

4. A yielding dovetail construction for combination with the hinged door of an automobile mounted to swing about a substantially vertical axis, said construction comprising a receiving device and a projecting device which engages the receiving device when the door is closed, said projecting device comprising a pair of spring tongues yieldable vertically about axes transverse to the plane of the door to move toward and from each other, and a cushioning body of yieldable material interposed between said spring tongues thereby giving more resistance to the spring members.

In witness whereof, I have hereunto subscribed my name.

WILLIS STUTSON.
